U.S. Cl. D56—2

FIG. 2

FIG. 3

FIG. 4

FIG. 5

FIG. 6

FIG. 1 is a perspective view of an attachment pedal for electric, spinet-type organs, showing my new design; FIG. 2 is a top plan view; FIG. 3 is a side elevational view, the opposite side being substantially a mirror image thereof;

FIG. 4 is a bottom plan view;

FIG. 5 is a rear end elevational view; and

FIG. 6 is a front end elevational view thereof.

The broken line fragmentary showing of a representative primary pedal of a spinet organ to which attachment pedal may be fastened is for illustrative purposes only.

I claim:

The ornamental design for an attachment pedal for electric, spinet-type organs, as shown and described.
